G. H. DILLON.
LAYING REGISTER FOR FOWLS.
APPLICATION FILED JUNE 24, 1916.

1,243,271.

Patented Oct. 16, 1917.

UNITED STATES PATENT OFFICE.

GEORGE H. DILLON, OF SAWTELLE, CALIFORNIA, ASSIGNOR OF ONE-HALF TO RICHARD H. ANGELL, OF SOLDIERS HOME, CALIFORNIA.

LAYING-REGISTER FOR FOWLS.

1,243,271.

Specification of Letters Patent.

Patented Oct. 16, 1917.

Application filed June 24, 1916. Serial No. 105,751.

To all whom it may concern:

Be it known that I, GEORGE H. DILLON, a citizen of the United States, residing at Sawtelle, in the county of Los Angeles and 5 State of California, have invented a new and useful Laying-Register for Fowls, of which the following is a specification.

An object of this invention is to provide practical means whereby the laying capacity 10 of hens and other fowls may be positively determined so that the drones may be separated from the more profitable fowls and the profitable fowls may be classified and separated into graded flocks, kept in 15 different yards for improvement of breeds and for exact determination of profits.

Further objects are, simplicity, cheapness, facility of applying and removing the device to and from the fowls, facility for 20 cleaning, disinfecting, sterilizing and freeing from vermin and to provide a light strong appliance for this purpose which will not inconvenience the fowl nor diminish her productiveness nor deter her from 25 laying, and which can not be pecked or scratched off or be otherwise removed by the fowl.

Other objects, advantages and features of novelty may appear from the accompanying drawings, the subjoined description and the appended claims.

The accompanying drawings illustrate the invention in the form at present deemed most desirable.

35 Figure 1 is a view of the laying register in position on a hen.

Fig. 2 is a side view of the same detached, the fastening clips being open.

40 Fig. 3 is an elevation of the other side of the register detached, the clips being closed.

Fig. 4 is a rear view of the register detached.

45 Fig. 5 is a reduced view of a sheet metal stamping in which the body and the bearings and sockets thereof shown in the other figures may be bent.

Fig. 6 is a plan view of a register constructed in accordance with this invention 50 with the indicator located at the front end of the body.

The body 1 is a light strong member of aluminum or other suitable material preferably in a sheet form having the edges 2 seamed or lapped over to increase rigidity 55 and to form sockets and bearings to receive and secure various elements of the device.

Fastening means 3 are applied to one end of said body and are shown as clips formed of bent wire limbs integral with a straight 60 central journal member 4 that is journaled to the body 1 by a loop 5 bent from the end of the main body 1.

Said body 1 is also provided with lateral loops 6 forming sockets to receive the 65 straight tips 7 of the clips 3. Said clips are bent to extend from the sides of the body, downward and back underneath the wings of the fowl and then up to the sockets 6, and are of a resilient nature being made of 70 spring steel or other suitable wire and covered with soft cushion-like sheaths 8 which may be made of rubber tubing or other suitable material adapted to prevent chafing the wings or body of the fowl and also 75 adapted to receive and retain an antiseptic and fumigating solution to serve as a protection of the fowl against parasites.

The straight tips 7 may be inserted into the sockets 6 by springing the clips 3 for 80 that purpose, and are held in place by the resiliency of the clips.

The sockets 6 may be bent from a single piece and may be slidingly adjustable along the body 1 to slide onto or off of the tips 7 85 if that method of connecting the sockets and tips together is preferred. The sockets may be made stationary on the body by any suitable means, as by swaging so as to be movable only by the application of considerable force.

All of this will be understood by anyone skilled in the art of making wire and sheet metal articles with and without sliding parts.

95 The cushions 8 may be provided with porous receptacles 8' for containing asafetida or other disinfectant or an insecticide to free the fowl from vermin and to conserve its health.

100 The main frame, comprising the body 1 and the parts formed integral and rigid

therewith, is adapted to fit easily upon the back of the fowl between the wings and extend from in front of the wings to in front of the tail.

5 At the rear end of the body 1, register operating means in the form of a swinging lever 9 is journaled to the body 1 by axis 10 in a transversely extending indicator cylinder 11 journaled in the box 12 formed at 10 the rear end of the body 1, so that the free end of the lever 9 may move toward and from the body of the fowl.

Said register lever 9 is preferably an elongate loop of wire having an orifice 13 between its side limbs to accommodate and to be held by the tail of the bird and to allow the free passage of excrement, but adapted to be actuated by an egg as it is laid.

The limbs of the loop 9 extend down on 20 each side of the orifice 13 and are bent at the lower end toward each other and are preferably cushioned as at 14, 15, to form egg-receiving parts in position to be acted upon by the egg in the operation of laying.

25 The cushions 14, 15, may be of rubber tubing or other suitable material of the same character as the cushions 8 of the wing loops. The transverse journal 10 of the register lever 9 is adapted to receive a short 30 cushion 15 of the same character as the cushions 8 and 14 and connects the side limbs of the register lever 9 and completes the loop thereof.

The box 12 is formed of a rear extension 35 *a* of the body 1 having a terminal tongue *b* adapted to enter slits *c* in the rear end of the body 1. The extension *a* is provided with an orifice *d* to expose the ordinals *e* on the indicator cylinder 11 when the device is 40 assembled.

The ordinals *e* are arranged on the cylinder 11 to be exposed successively through the orifice *d* as the indicator cylinder is turned step by step through the actuation of 45 the lever 9 and means connecting the same with the indicator cylinder to rotate said cylinder. Said means may be variously constructed and are shown as a pawl 16 mounted on the lever 9 and a ratchet wheel 17 fixed 50 to the cylinder and having its teeth 18 equal in number to the ordinals *e*, of which there may be twelve, more or less. A second ratchet wheel 19 having a corresponding number of teeth 20 is fixed to the cylinder 55 at the other end and is engaged by a pawl 21 fastened to the body 1 by the lateral loop 22 and adapted to prevent backward rotation of the indicator cylinder 11. By this arrangement, as the egg is expelled by the 60 hen or other fowl it operates the limb 9 to actuate the record cylinder so that the number of eggs laid by a fowl will be registered. Since the fowl is not expected to lay more than one egg a day, the register shown in 65 the drawings is adapted for a period of

twelve days provided the hen lays one egg each day.

In the form shown in Fig. 6 the indicator housing 23 is mounted at the front end of the body 1'' and a flexible connection 24 is 70 connected at one end to a spring 25 that is accommodated in the lap 2'' of the body 1''. The connection 24 passes around the indicator cylinder 26 and is connected at the other end to a cylinder 27 that is journaled in the 75 box 12'' corresponding to the box 12 shown in Fig. 2. Said cylinder 27 is connected to the lever 9' and moves therewith when said lever is actuated by the egg in the act of laying. The connection while thus being 80 actuated is held tightly against the cylinder 26 by the action of the spring 25, thus causing said cylinder to rotate when the lever drops down. After the egg has been laid the spring returns the slack connection 24 85 to normal position and the ratchet 28 prevents the indicator cylinder from returning. In this way the indicator cylinder will be made to move one number as each egg is laid.

90 In practical use the registers will be applied respectively to the fowls to be tested and from day to day, or at the end of the determined period, say, twelve days, the register of each fowl will be inspected and 95 its indication noted. If desired the register may then be set to zero and another test be made with the same fowl.

If the indicator shows full twelve eggs laid in the twelve days, the fowl will be 100 placed in the A1 class, and may be marked with any suitable tag and segregated in a separate yard for breeding purposes. Other fowls will be also classified according to the 105 number of eggs laid and tagged and segregated if desired. The drones may be placed in a yard set aside for them and subjected to further tests.

I claim:—

1. In a laying register, a frame adapted 110 to fit the back of a fowl between the wings and extend from in front of the wings to in front of the tail, a transverse bearing at the front end of the frame, a wire having a central portion journaled in the bearing and 115 bent to form wing embracing loops on each side of the bearing, sockets mounted at the center of the frame to receive the free ends of the loops, a housing carried by the rear end of the frame, an indicator cylinder in 120 the housing, a lever pivotally mounted and adapted to be operated by the egg in the laying process, and a pawl and ratchet connection between the lever and the cylinder.

2. In a laying register, a frame adapted 125 to fit the back of a fowl between the wings and extend from in front of the wings to in front of the tail, wire loops extending from the front end of the frame and adapted to attach the frame to the wings, and in- 130

dicator mechanism carried by the frame and adapted to be operated by the egg in the laying process.

3. In a laying register, a frame adapted to fit the back of a fowl between the wings and extend from in front of the wings to in front of the tail, means extending from the front end of the frame for attachment to the wings for holding the frame in place, and

indicator mechanism carried at the rear end 10 of the frame and adapted to be operated by the egg in the laying process.

In testimony whereof, I have hereunto set my hand at Los Angeles, California, this 17th day of June, 1916.

GEORGE H. DILLON.

Witness:

JAMES R. TOWNSEND.
